HIGH CHAIR

Robert L. Hail and Alice L. Hail, Colorado Springs, Colo.

Application July 27, 1955, Serial No. 37,142

Term of patent 14 years

(Cl. D15—1)

FIG. 1

FIG. 2

FIG. 3

FIG. 4

Fig. 1 is a front elevation of a high chair embodying our new design.

Figs. 2 and 3 are, respectively, a side elevation and a top plan view of the high chair illustrated in Fig. 1.

Fig. 4 is a perspective view of the high chair in lowered position with the tray element removed.

We claim:

The ornamental design for a high chair, as shown.
